CLAIM

(21) **Appl. No.:** **29/577,873**

The ornamental design for a valve cover, as shown and described.

(22) **Filed:** **Sep. 16, 2016**

DESCRIPTION

(51) **LOC (12) Cl.** **29-02**

FIG. 1 is a right top perspective view of a valve cover in accordance with our new design;

(52) **U.S. Cl.**

FIG. 2 is a top plan view thereof;

(58) **Field of Classification Search**

FIG. 3 is a front elevation thereof;

USPC D24/110.1; D24/129; D24/110.1

FIG. 4 is a rear elevation view thereof;

USPC D24/110.6; D24/129; D24/110.1

FIG. 5 is a left side elevation view thereof, the right side elevation view is a mirror image thereof;

USPC D23/332, 335, 355, 356, 366, 388, 412;

FIG. 6 is a bottom plan view thereof;

D29/102, 105, 106; D3/272, 273, 302,

FIG. 7 is a left bottom perspective view thereof;

D3/903; D9/420, 430, 432

FIG. 8 is a right top perspective view thereof and shown attached to a base; and,

CPC A62B 18/025; A62B 18/02; A62B 9/02;

FIG. 9 is a right top perspective view of FIG. 8 and shown attached to a respirator.

A62B 18/084; A62B 23/02; A62B 7/10;

The diagonal surface shading lines indicate that the surface of the valve cover is either transparent or translucent as further described herein.

A62B 18/08; A61M 16/208; A61M

16/201; A61M 16/207; A61M 16/20;

16/20; A61M 16/06; A61M 16/0003; A61M

16/206

The gray surfaces of the valve cover are translucent. The remaining claimed surfaces, other than the gray surfaces, of the valve cover are transparent.

16/206

The dash-dash broken lines showing the base in FIGS. 8-9

and the respirator in FIG. 9 depict environment and form no

part of the claimed design. All other dash-dash broken lines

depict portions of the valve cover that form no part of the

claimed design.
